(57) **CLAIM**

The ornamental design for a lighting ornament, as shown and described.

DESCRIPTION

FIG. 1 is a front perspective view of a lighting ornament;

FIG. 2 is a top view thereof;

FIG. 3 is a left side view thereof;

FIG. 4 is a right side view thereof;

FIG. 5 is a bottom side view thereof;

FIG. 6 is a front view thereof; and,

FIG. 7 is a rear view thereof.

The broken line showing of a portion of the lid is included for the purpose of illustrating only and forms no part of the claimed design.
